POWDER CAN TOP

Albert L. Davis, Watertown, Conn., assignor to
 The Waterbury Brass Goods Corporation,
 Waterbury, Conn., a corporation of Connecticut

Application November 3, 1932. Serial No. 640,948

7 Claims. (Cl. 221—64)

This invention relates to new and useful improvements in powder can tops, and has for an object to provide a powder can top of simple construction and including a cover or closure for the discharge opening or openings of the top, which cover or closure may be operated between open and closed positions by the thumb or a finger of the hand in which the powder can equipped with the top is held.

10 Other objects and advantages will become apparent from a consideration of the following detailed description taken in connection with the accompanying drawing wherein satisfactory embodiments of the invention are shown. However, it will be understood that the invention is not limited to the details disclosed but includes all such variations and modifications as fall within the spirit of the invention and the scope of the appended claims.

20 In the drawing:

Fig. 1 is a front elevational view showing a powder can including a top constructed according to the present invention, the closure or cover of the top being in open position;

25 Fig. 2 is a view of the top and the upper portion of the can, the top cover or closure being shown in closed position;

Fig. 3 is a plan view of the top as shown in Fig. 2;

30 Fig. 4 is an enlarged central sectional view through the top;

Fig. 5 is a view similar to Fig. 1 but showing a slight modification;

Fig. 6 is a further view of the top of Fig. 5, its cover or closure being shown in closed position; and

Fig. 7 is a side elevational view of the forward portion of the top.

Referring in detail to the drawing and at first particularly to Figs. 1 through 4, at 10 is shown the body of a can of any desired construction and configuration and which is adapted to receive powder as for example tooth powder. Telescopically receiving the upper end portion of the can body 10 is my improved powder can top generally designated 11, and as the description proceeds it will become evident that the top 11 may be applied to the can body in a manner other than by telescopically receiving the upper end portion of the can body.

50 Top 11 includes an upper wall 12 from which depends an annular flange or skirt-like portion 13 which receives the upper end portion of the can body. Projecting upwardly or outwardly from the upper or top wall 12 is an extension 14

open at its inner side whereby it is in communication with the interior of the can body and including an upwardly inclined forward wall 15 and a downwardly inclined transversely curved upper wall 16 and substantially straight side walls 17. The forward wall 15 has its central portion inwardly offset as at 18, and is preferably adjacent its upper edge provided with a discharge opening 19.

A cover or closure 20 is disposed against the inwardly offset portion of wall 15 and lies substantially flush with the outer face of said wall, and is substantially in the form of a disc centrally pivoted to the wall as by a rivet or the like 21. This cover or closure 20 is provided with a discharge opening 22 adapted to be brought into registry with the opening 19 whereby the contents of the can may be dispensed. A lug or finger piece 23 is formed with or secured to the cover or closure 20 and includes a portion extending over the curved wall 16 of the extension 14 to ride thereon as clearly shown in Figs. 3 and 4.

The pivot 21 for the closure or cover is concentric with respect to the wall 16 of the extension and the operating lug or finger piece 23 lies against this wall and may be engaged by a finger or thumb and shifted to shift the closure between closed and open positions. That is, the lug 23 may be operated to shift the closure to take the opening 22 out of registry with the opening 19 or into registry with it. The parts are preferably so arranged that when the lug is shifted to move the closure and bring its opening 22 into registry with the opening 19 of the forward wall of the extension the said lug engages the straight side wall 17 of said extension when said openings come into registry.

Therefore, this side wall forms a stop and limits movement of the closure in one direction about its pivot, and when it is desired to use some of the contents of the can the operator simply shifts the lug 23 downwardly from the position in which it is shown in Figs. 2 and 3 into the position in which it is shown in Fig. 1, and when further movement of the closure is prevented by engagement of the lug with one of the walls 17, the operator is advised that opening 22 is in registry with opening 19. There is no need or occasion for careful manipulation of the cover 20 when returning it to closed position since it cannot be given an excessive movement as the lug 23 would engage the opposite straight wall 17 of the extension. From

this it will be apparent that movement of the cover in either direction is limited.

From the foregoing description it will be apparent that the can 10 equipped with my improved top may be grasped in one hand as shown in Fig. 1 and that the cover or closure 20 may be operated by the thumb or a finger of the hand supporting the can. When the cover has been shifted to open position the can may be inverted or otherwise manipulated to place powder on a toothbrush grasped in the other hand of the operator. When sufficient powder has been dispensed it is apparent that the closure may be easily returned to closed position and the can replaced in a cabinet or the like. The extension 14 acts as a guide or funnel to direct the powder to the discharge opening 19, and while reference has been made to the can as used for dispensing toothpowder, it will be obvious that it may be used as a dispensing container for other kinds of powder.

Referring now to Figs. 5, 6 and 7, the top 11 is of substantially the construction above described, and includes the extension 14 above described. However, in these figures the forward wall 15 of the extension is provided with a plurality of relatively small openings 24, and the cover member designated 25 is pivoted against this wall as by the rivet 21 and is provided with a plurality of perforations 26 adapted to be brought into and out of registry with the perforations 24 as the cover is moved to opened and closed positions. This cover 25 is provided with a lug 27 of the same construction and having the same functions as the lug 23 of Figs. 1, 2 and 4.

Since in Figs. 5, 6 and 7 a plurality of perforations are involved forming a sifter top, the movement of the cover should be limited in both directions about its pivot, so that at the limit of its movement in one direction it is in open position with its perforations registering with those of the forward wall of the extension and at the limit of its movement in the opposite direction it is in closed position with its openings or perforations out of registry with those in the forward wall of the extension. As will be understood, the lug 27 will engage a side wall 17 of the extension to limit movement of the cover in one direction or to open position.

The cover or closure is provided with a second radially extending lug 28 and when the cover is shifted to closed position this lug engages the upper or top wall 12 of the improved top and prevents further movement of the closure in one direction. Therefore, it will be understood that movement of the closure in either direction is limited so that the operator need not look to see if the device is open or closed but will know that it is open when lug 27 has been moved down as far as possible and that it is closed when said lug has been moved up as far as possible, since in this latter position lug 28 will have engaged the upper wall 12 of the top. Attention is particularly directed to the fact that stops or limiting means are provided without the addition of unsightly protuberances. Further, as the lugs 23 and 27 of the respective forms ride on the curved wall 16 a smooth movement of the cover is obtained and there is such friction present that the cover stays in adjusted position.

Having thus set forth the nature of my invention, what I claim is:

1. In a powder can top, a hollow body, an extension at the upper side of said body and open at the inner side thereof, said extension

including a forward wall arranged at an angle to the upper surface of the body and said extension inclining from said wall and forming a funnel like portion leading to said wall, said wall having a discharge opening therein, a closure pivotally mounted against said wall and having an opening therein, and said closure turnable between an open position with its opening registering with the opening in the wall and a closed position with its opening out of registry with the opening in the wall, and a stop lug on said closure in position to engage a wall on the top to limit turning movement of the closure. 80

2. In a powder can top, a hollow body, an extension at the upper side of said body and open through the inner side thereof, said extension including a forward wall, a curved top and substantially straight side walls, said top and side walls inclining from said forward wall whereby said extension forms a funnel like portion leading to said forward wall, said forward wall having a circular depression in its front face, a disc shaped closure pivotally mounted against said forward wall and within said depression so as to be flush with the outer surface of said wall, each of said forward wall and said closure having an opening therein, a lug on said closure and projecting rearwardly over said extension, said closure mounted concentric with the curved top wall of the extension and shiftable to carry its opening out of and into registry with the opening in the forward wall of the extension, and one of said side walls of the extension arranged to be engaged by said lug and form a stop for said closure when the closure is shifted to bring its opening into registry with the opening in the said forward wall. 95

3. In a powder can top, a hollow body, an extension at the upper side of said body and open through the inner side thereof, said extension including a forward wall, a curved top wall and side walls whereby said extension forms a funnel like portion leading to said forward wall, a closure pivotally mounted against said forward wall, each of said forward wall and said closure having an opening therein, a lug on said closure and projecting rearwardly over said extension, said closure mounted concentric with the curved top wall of the extension and shiftable to carry its opening out of and into registry with the opening in the forward wall of the extension, and one of said side walls of the extension arranged to be engaged by said lug and form a stop for said closure when the closure is shifted to bring its opening into registry with the opening in the said forward wall. 100

3. In a powder can top, a hollow body, an extension at the upper side of said body and open through the inner side thereof, said extension including a forward wall, a curved top wall and side walls whereby said extension forms a funnel like portion leading to said forward wall, a closure pivotally mounted against said forward wall, each of said forward wall and said closure having an opening therein, a lug on said closure and projecting rearwardly over said extension, said closure mounted concentric with the curved top wall of the extension and shiftable to carry its opening out of and into registry with the opening in the forward wall of the extension, and one of said side walls of the extension arranged to be engaged by said lug and form a stop for said closure when the closure is shifted to bring its opening into registry with the opening in the said forward wall. 105

4. In a powder can top, a hollow body, an extension at the upper side of said body and open at the inner side thereof, said extension including a forward wall arranged at an angle to the upper surface of the body and said extension inclining from said wall and including substantially parallel side walls forming a funnel like portion leading to said wall, a closure, means pivotally mounting the closure on said wall, said wall having a discharge opening therein adjacent its upper edge, said closure having an opening therein, and said closure shiftable on its pivot between an open position with its opening registering with the opening in the wall and a closed position with its opening out of registry with the opening in the wall. 115

5. In a powder can top, a hollow body, an extension at the upper side of said body and open through the inner side thereof, said ex- 120

tension including a forward wall, a curved top wall and straight side walls whereby said extension forms a funnel like portion leading to said forward wall, a closure pivotally mounted 5 against said forward wall, each of said forward wall and said closure having an opening therein, a lug on said closure and projecting rearwardly over said extension, said closure mounted concentric with the curved top wall of the extension whereby said lug may ride on said wall, 10 said closure shiftable to carry its opening out of and into registry with the opening in the forward wall of the extension, and said straight side walls arranged to be engaged by said lug and form stops to limit movement of said closure in both directions about its pivot.

6. In a powder can top, a hollow body, an extension at the upper side of said body and open through the inner side thereof, said extension including a forward wall, a curved top wall 15 and side walls whereby said extension forms a funnel-like portion leading to said forward wall, a closure pivotally mounted against said forward wall, each of said forward wall and said closure having a plurality of openings, a pair of spaced lugs on said closure and extending radially therefrom, one of said lugs including a finger engaging portion projecting rearwardly over said extension, said closure mounted concentric with the curved top wall of the extension 20

30

and shiftable between an open position with its openings registering with the openings in the said forward wall and a closed position with its openings out of registry with those in said wall, one of said straight side walls arranged to be engaged by said lug having the finger engaging portion and form a stop for the closure when it is in one position, and the other of said lugs arranged to engage the upper side of said hollow body portion and form a stop for the closure when the latter is in the other of its positions. 85

7. In a powder can top, a hollow body, an extension at the upper side of said body and open through the inner side thereof, said extension including a forward wall, a curved top wall and side walls whereby said extension forms a funnel-like portion leading to said forward wall, a closure pivotally mounted against said forward wall, each of said forward wall and said closure having an opening therein, a lug on said closure and projecting rearwardly over said extension, said closure mounting concentric with the curved top wall of the extension and shiftable to carry its opening out of and into registry with the opening in the forward wall of the extension, and one of said side walls of the extension arranged to be engaged by said lug and form a stop for said closure when the latter is in one of its positions. 95
